(57) **CLAIM**

A housing for a compressor, as shown and described.

DESCRIPTION

FIG. 1 is a top-right perspective view of a housing for a compressor showing my new design;

FIG. 2 is an end view a housing for a compressor shown in FIG. 1;

FIG. 3 is an opposite end view of a housing for a compressor shown in FIG. 2;

FIG. 4 is a top view of a housing for a compressor as shown in FIG. 1;

FIG. 5 is a side view of a housing for a compressor shown in FIG. 1; and,

FIG. 6 is a bottom view of a housing for a compressor shown in FIG. 1.

The elements shown in broken lines form no part of the claimed design.
